UNITED STATES PATENT OFFICE.

ROBERT CAIRNS AND JOSEPH W. CAIRNS, OF WATERTOWN, WISCONSIN.

COIN-DELIVERY MACHINE.

Application filed July 24, 1920. Serial No. 398,609.

To all whom it may concern:

Be it known that we, ROBERT CAIRNS and JOSEPH W. CAIRNS, citizens of the United States, residing at Watertown, in the county 5 of Jefferson and State of Wisconsin, have invented new and useful Improvements in Coin-Delivery Machines, of which the following is a specification.

This invention relates to change-making 10 and other coin-delivery machines, and more particularly to the mechanism for selectively operating the coin-ejecting devices, the object of the invention being to provide a novel and improved electrically operated mechanism which can also be operated manually.

The object stated is attained by means of a combination and arrangement of parts to be hereinafter described and claimed, and in order that the same may be better understood, reference is had to the accompanying drawings forming a part of this specification.

In the drawings,

Figure 1 is a side elevation of the machine;

Fig. 2 is a front elevation thereof;

Fig. 3 is an enlarged cross section;

Fig. 4 is a diagrammatic section on the line 4—4 of Fig. 3, and

Fig. 5 is a section on the line 5—5 of Fig. 3, a fragment only of the mechanism being shown.

Referring specifically to the drawings, 10 denotes the casing of the machine, the same being constructed and equipped with suitable supporting means for the various elements which make up the coin-delivery mechanism. The front of the casing has a plurality of coin chutes 11 designed to support coins of different denominations in stacks. With each coin chute is associated an ejector 12 for pushing the bottom coin from beneath the stack. The ejector 12 is carried by a slide block 13 mounted on a 20 guide stem 13^a, and connected by a link 14 to one arm 15 of an angle lever having its other arm 16 connected by a link 17 to a bracket arm 18 on a reciprocating stem 19 working between guide rollers 20. The angle lever 25 is fulcrumed, as shown at 21, to a support 22 in the casing 10. The ejector device is disclosed in the application filed June 17, 1920, Serial No. 389,651, and hence a further description thereof in the present application is not necessary. It will be apparent 35 that the ejector 12 is advanced to deliver a

coin when the stem 19 moves downwardly, and on the return stroke of the stem, the ejector is retracted.

The ejector mechanism is operated and controlled by depressible keys 23, each having its stem 24 fitted with a cross bar 25 provided with one or more lugs 26 adapted to engage a corresponding number of longitudinal bars 27, each of which latter is 65 equipped with a stem 19. The machine is shown provided with one hundred keys for making change from one cent to one dollar, and one extra key to deliver a single dollar. When a key 23, corresponding in value to 70 the desired change, is depressed, the bar 25 on the stem of said key, through its lugs 26 depresses the bars 27 in the path thereof, and the latter through the stems 19 and the connections hereinbefore described, operate 75 the ejectors 12 required to eject the desired amount. As this selector mechanism is well known in the art, a further description thereof is not necessary. The bars 27 work and are guided at their ends in slots 28 in guide 80 bars 29.

Thus far described the apparatus is operated manually by depressing the keys 23. The apparatus is also provided with a means whereby it may be operated electrically at 85 will. This means will now be described.

Alongside each bar 27 is positioned a parallel auxiliary bar 30 which is in the path of auxiliary lugs 31 so as to be actuated thereby when the keys 23 are depressed, 90 these lugs being on the cross bars 25 of the key stems 24. Thus, when the keys 23 are depressed the bars 27 as well as the bars 30 are pushed downwardly. The bars 30 however are not provided with stems 19 for actuating the ejectors 12, but instead, each bar 30 has a depending rod 32 passing through a spring 33 bearing at one end against an abutment 34 on the rod and seating at its other end on a support 35. These springs 100 are for the purpose of giving the bars 30 a return stroke after they have been depressed. Similar springs 36 are provided for the bars 27, the same being coiled around the stems 19.

Each stem 19 is connected to the slidable 105 plunger 37 of a solenoid 38, and hence it will be seen that the stem is drawn down to operate the ejector 12 when the solenoid is energized.

The circuits of the solenoids 38 are controlled by switches consisting of contacts 39 carried by the auxiliary bars 30, and each

positioned opposite another contact 40. Each contact 40 is carried by a rocker arm 41 pivoted intermediate its ends, as shown at 42, to a post 43 on the support 22. To the 5 end of the arm 41 opposite the end carrying the contact 40 is connected a spring 44 anchored to the post 43. On the same side of the rocker arm 41 as the spring 44 is a lug 45 which engages the post 43 and thus limits 10 the swing of the contact 40 toward contact 39. The contacts 40 are all mounted on a bar 46 of insulating material carried by a pair of the hereinbefore described rocker arms 41. Each pair of contacts 39 and 40 is wired 15 to a solenoid corresponding to ejector mechanism which is controlled by the respective bars 30.

It will be evident from the foregoing that when a key 23 is depressed to depress one or 20 more auxiliary bars 30, the circuits of corresponding solenoids 38 are closed, whereupon the stems 19 connected to the plungers 37 of said solenoids and the bars 27, but not the auxiliary bars 30, are drawn down to 25 operate the ejector or ejectors 12 connected to said stems.

An angle-beam 47 is secured across the casing 10 to provide bearings 48 for a rock shaft 49 having U-shaped bends 50 closed 30 on one side by soldered plates 51. A bend 50 is opposite each rod 32 and a finger 52 extends from said rod into the nose of the bend. These parts have no function, ordinarily, but when the electric actuating means 35 are out of order the shaft 49 is rocked in a clockwise direction as viewed in Fig. 3, by means of the crank-handle 53^a connected thereto on the outside of the casing 10, whereby, through the parts 51 depressing 40 the fingers 52, all the auxiliary bars 30 are lowered out of reach of the key stems 24. This action, of course closes the circuits of 45 the solenoids at the contacts 39 and 40 and depresses the rocker arms 41, but the circuits are broken at another point as follows:

On the beam 47, and insulated therefrom is a contact 53, and the shaft 49 carries an insulated contact 54 on one of the bends 50. These contacts are normally together, but 50 they are separated when the shaft 49 is rocked as hereinbefore described. The contacts 53 and 54 are wired to the main feed connection of the solenoids 38, and hence it will be seen that the latter cannot be energized when said contacts are separated. The machine can now be operated manually by 55 pressing the keys 23 as usual.

The crank handle 53^a has a spring latch pin 55 provided with an actuating knob 56, and adapted to enter keeper apertures in the casing wall for locking the handle and its shaft 49.

In the operation of the machine, the selected key 23 is held down until the coin 60 is ejected, and the key is then released,

whereupon it is elevated by a key-lifting spring to separate the contact 39 from the contact 40 and break the circuit of the solenoid. The key-lifting springs are shown at 23^a in Fig. 3. The solenoids operate at a 70 very high speed, and hence a momentary depression of a key 23 suffices to obtain a complete working stroke of the ejecting mechanism.

We claim:

1. In a coin-delivery machine, coin ejectors, and means for selectively operating the ejectors, said means comprising electro-responsive means having actuating connections with the ejectors, said connections being also manually operable, and including selectors and keys for operating said selectors, an energizing circuit for the aforesaid electro-responsive means, switches controlling the electro-responsive means, and means actuated by the aforesaid keys for selectively operating the switches.

2. In a coin-delivery machine, coin-ejectors, and means for selectively operating the ejectors, said means comprising electro-responsive means having actuating connections with the ejectors, said connections being also manually operable, and including selectors and keys for operating said selectors, an energizing circuit for the aforesaid electro-responsive means, switches controlling the electro-responsive means, means actuated by the aforesaid keys for selectively operating the switches, and means for placing said switch operating means in inoperative position.

3. In a coin-ejecting machine, coin-ejectors, and means for selectively operating the ejectors, said means comprising electro-responsive means having actuating connections with the ejectors, said connections being also manually operable, and including selectors and keys for operating said selectors, an energizing circuit for the aforesaid electro-responsive means, switches controlling the electro-responsive means, means actuated by the aforesaid keys for selectively operating the switches, and means for placing said switch operating means in inoperative position and for opening the energizing 105 circuits of the electro-responsive means.

4. In a coin-delivery machine, coin-ejectors, and means for selectively operating the ejectors, said means comprising electro-responsive means having actuating connections 120 with the ejectors, said connections being also manually operable, and including selectors and keys for operating said selectors, an energizing circuit for the aforesaid electro-responsive means, switches controlling the 125 electro-responsive means, means actuated by the aforesaid keys for selectively operating the switches, and means for opening the energizing circuits of the electro-responsive means.

5. In a coin-delivery machine, coin-ejectors, and means for selectively operating the ejectors, said means comprising electro-responsive means having actuating connections with the ejectors, said connections being also manually operable, and including selectors and keys for operating said selectors, an energizing circuit for the aforesaid electro-responsive means, switches controlling the electro-responsive means, means actuated by the aforesaid keys for selectively operating said switches, and means independent of the keys for opening the energizing circuit of the electro-responsive means.
- 10 6. In a coin-delivery machine, coin-ejectors, and means for selectively operating the ejectors, said means comprising electro-responsive means having actuating connections with the ejectors, said connections being also manually operable, and including selectors and keys for operating said selectors, an energizing circuit for the aforesaid electro-responsive means, auxiliary selectors operated by the aforesaid keys, and switches controlling the electro-responsive means, said switches being actuated by the auxiliary selectors.
- 15 7. In a coin-delivery machine, coin-ejectors, and means for selectively operating the ejectors, said means comprising electro-responsive means having actuating connections with the ejectors, said connections being also manually operable, and including selectors and keys for operating said selectors, an energizing circuit for the aforesaid electro-responsive means, auxiliary selectors operated by the aforesaid keys, switches controlling the electro-responsive means, said
- 20 switches being actuated by the auxiliary selectors, and means for placing the auxiliary selectors in inoperative position.
- 25 8. In a coin-delivery machine, coin-ejectors, and means for selectively operating the ejectors, said means comprising electro-responsive means having actuating connections with the ejectors, said connections being also manually operable, and including selectors and keys for operating said selectors, an energizing circuit for the aforesaid electro-responsive means, auxiliary selectors operated by the aforesaid keys, switches controlling the electro-responsive means, said switches being actuated by the auxiliary selectors, and means for placing the auxiliary selectors in inoperative position and for opening the energizing circuit of the electro-responsive means.
- 30 9. In a coin-delivery machine, coin-ejectors, and means for selectively operating the ejectors, said means comprising electro-responsive means having actuating connections with the ejectors, said connections being also manually operable, and including selectors and keys for operating said selectors, an energizing circuit for the aforesaid electro-responsive means, auxiliary selectors operated by the aforesaid keys, switches controlling the electro-responsive means, said switches being actuated by the auxiliary selectors, and means for opening the energizing circuit of the electro-responsive means.
- 35 In testimony whereof we affix our signatures.
